METHOD OF TREATING CYPRESS

Application filed July 30, 1928. Serial No. 296,128.

This invention relates to wood flooring and method of preparing same. While the invention is directed particularly toward flooring, it is to be understood that the invention is concerned primarily with the making of wood surfaces also useful for doors, paneling, cabinet construction, woodwork, or the like. The invention is also concerned with the flooring itself, and the manner in 10 which it is laid.

The invention contemplates the making of flooring or rather wooden tile, wherein the grain of the wood is positioned on end and in which the wood is made up into completed 15 tile-like units so that when the units are laid for forming a floor the floor is complete and no other finishing or dressing operations are required. One of the most essential features of the invention resides in the steps by 20 means of which the wood is treated to effect a finished wearing surface, as will be brought out in more detail later in the specification.

In the accompanying drawings:

Fig. 1 is a perspective view of a wooden 25 timber which may be used in making up the flooring.

Fig. 2 is a perspective view of the same after it has been cut to the proper cross section.

Fig. 3 is a perspective view of a number 30 of timbers secured together and illustrating how tile-like sections are sliced from this composite timber.

Fig. 4 is a perspective view of the finished 35 flooring.

Fig. 5 is a detail of the manner in which the floor is laid.

Fig. 6 is a detailed sectional view similar 40 to Fig. 5 showing a modification wherein a fabric floor covering is used with an insert.

Inasmuch as this invention contemplates the use of wood in which the grain is laid on end, and inasmuch as a number of the pieces 45 of wood may be made up into a tile-like section having any desired design, it is preferable to employ wood in which the shrinkage is end-wise, and which has a minimum of shrinkage transverse of the grain. Examples 50 of such woods are cypress, redwood, and

cedar, although there may be other woods suitable for the purpose.

Suitable timbers such as 1, of the desired wood, are preferably first kiln-dried and then the timbers may be cut lengthwise to give 55 the same the desired cross section, as shown at 2. In the form shown, four timbers 2 may be used with one of the timbers 1 which may be placed together as shown in Fig. 3, so that the end forms the design as shown. 60 This design is shown for exemplary purposes only for it is to be appreciated that an innumerable number of designs may be effected.

The timbers, as shown in Fig. 3, are now 65 securely fixed together and this may be accomplished by gluing the timbers together, holding them compressed tightly together as the glue sets. Preferably a very good grade of glue which is water-proof is used.

After this glue has dried and the timbers are securely fixed together the composite block is cut cross-wise thus to form a wooden tile 3. This tile of course has a design the 70 same as the design effected in the making of the original composite timber.

The tiles are now treated in a solution which effects a hardening of the wood and which also preferably effects fire-proofing of the wood. This may be done by depositing the tiles in a bath of the solution for a suitable length of time. The solution used is preferably a solution which, upon evaporation, leaves deposits of solid materials in the 75 wood. Examples of the solutions which may be used are, sodium silicate, zinc oxide, aluminum sulphate, and ammonium sulphate.

It has been found that some of these solutions work to more advantage with a particular kind of wood than other solutions, and sodium silicate is perhaps the most preferable of the solutions mentioned because it is found that it works satisfactorily with the several woods and because of its cheapness.

After the wooden tiles are thus treated, at least one surface is finished as by means of sandpapering and buffing. Following this the wooden tiles are treated with oil which may be done by dipping the tiles in an oil bath or by merely applying oil to the buffed 95 100

surface. The wooden tiles need not necessarily be soaked in oil inasmuch as the dipping process lasting but a few minutes has been found sufficient.

5 The particular oil used can be varied as desired, but it has been found that a cheap paraffin base oil will suffice, and it is preferred to use this cheap oil which is in step with the contemplations of the invention in 10 providing a wooden flooring or the like which can be had at a market price more reasonable than which wooden flooring has heretofore been obtainable.

15 The treating of the wooden tile with the oil, following this treatment with the solution which leaves solid deposits is an important one. The solid deposits of the solution will occur in the pores of the wood in and around the fibres and when the wood is 20 subsequently treated with oil it is found that a polished appearance results as distinguished from the oily effect or appearance present when non-treated wood is oiled.

Moreover, the oil-treating step following 25 the hardening and fire-proofing of the wood brings out the color of the wood in addition to giving the same a polished appearance. Thus the tiles are entirely complete and ready to be laid into the floor or incorporated 30 into a panel, a door, or the like.

While there occurs this polished appearance, there is in reality no polished surface as there is in the case of a wooden floor which is varnished or waxed. This is desirable 35 because there is no surface finishing to wear away and which must be replaced from time to time inasmuch as the wood fibres are treated and which treatment extends into the wood so that in use the polished 40 appearance always remains although there may be a wearing away of the wooden fibres. Moreover, a floor constructed of this tile is advantageous because of the lack of a slick 45 surface. Accordingly, the floor has good gripping qualities, and there is practically no danger of one using the floor of slipping or falling.

A floor thus constructed of wooden tile is one which possesses long life and which requires 50 a minimum of attention. Its glossy appearance is a lasting one which does not wear away inasmuch as the appearance comes about by treatment of the fibres of the wood, and in fact its good appearance increases in 55 use if the same is dusted from day to day with an oil mop or the like. The floor does not become warped on account of the end grain arrangement of the wood inasmuch as all shrinkage in the wooden tile is vertical, 60 or rather, in the direction of the grain. Moreover, a floor constructed of the wooden tile is completed in its entirely upon the laying of the tile. It can be used immediately, there being no additional sanding or finishing operations 65 required.

The preferred manner of laying the floor is illustrated in Fig. 4 in which the wooden tile floor is floated upon its base. A conventional concrete flooring of a modern steel and concrete building is referenced 5 and the 70 wooden flooring is merely floated upon the concrete with no means of attachment thereto. The wooden tile pieces may be secured together as by means of corrugated metallic 75 tying members 6 which may be driven into two adjoining tiles. Of course the flooring may be laid upon a base of wood or other material, and it may be bonded to the base if desired rather than floating it on the base.

It is appreciated that the surface of a concrete floor, while being level in general, possesses a more or less pitted or irregular surface, as illustrated in Fig. 5. Accordingly, it is preferable to place a filler between the 80 wooden floor and the concrete of the base, for the purpose of absorbing such irregularities. This filler may be in the form of paper or composition board, and as shown in Fig. 5 the filler is in the form of paper board having exterior facings 7 and 8 with an interior corrugated member 9. This filler is more or less distortable and accommodates 85 for irregularities in the concrete and also acts as a silencer.

90 It is important to note that the filler used between the floor base and the wearing part of the floor can be of relatively cheap fiber board construction. Preferably the exterior layer 9 is of relatively light construction to permit the filler to adjust itself to the irregularities in the base, as clearly shown in Figs. 95 5 and 6. The layer 7, however, is preferably of thicker material and accordingly stronger and stiffer.

The interior corrugated member 8 distorts 100 somewhat at the corrugations which lie over a rise in the floor, and the filler provides a permanent air cushion between the base and the wearing part of the floor. It is preferable 105 that one or both of the exterior layers 7 and 9 be water-proofed. This prevents moisture in any appreciable degree from getting into the corrugated layer 8. Thus the 110 corrugated member possesses a long life and forms flooring which is more or less resili- 115 ent. In other words, when weight is on the floor, the corrugated portions are compressed or flattened out slightly, but this weight is distributed over an area sufficient to prevent 120 complete collapsing or destruction of the corrugated portions. These corrugated portions spring back in place when the weight is relieved from the floor.

125 This fiber board insert is also advantageous for use with the floors other than wood. For example, in Fig. 6, there is shown a floor wherein a fabric carpet 10 is laid over the fiber board insert. It has been the practice in many places to lay a thick felt pad underneath these carpets, but this is very 130

expensive and allows the carpet to wrinkle and fold so that it is difficult to make the carpet lie flat. By the use of this fiber board insert, however, the same hugs the floor base and is not subject to folding or wrinkling and at the same time the insert is relatively cheap. This insert will provide an air cushion for the flooring and the corrugated inner member will stand up under a long period of use, especially when the exterior layers are water-proof to prevent moisture from softening the inner corrugated member. In some of the claims appended hereto use is made of the term "surface member" of the floor and this term is intended to cover any floor covering, whether it be wood, carpet or other material.

Accordingly, it will be seen that a minimum of time and labor is required to lay the floor inasmuch as the wooden floor is merely floated upon the concrete or other base with no attachments to the base necessary. Also upon the completion of the laying of the floor it is ready for use. One of the primary features of this invention is the fact that a lasting wooden floor can be had at a cost materially less than wooden floors otherwise proposed and less than floors constructed of inferior materials. The cheapness of the solutions in which the wood can be treated is the fact that a low grade of oil can be used and the fact that the floor can be laid with a minimum of trouble and time, are factors which all enter into the provision of a floor obtainable at relatively low costs.

Claims:

1. The method of preparing cypress to adapt it primarily for use in floors, wall covering, cabinet work, or the like, in an end grain manner which comprises, treating the cypress with a solution of sodium silicate and an oil.

2. The method of preparing cypress to adapt it primarily for use in floors, wall covering, cabinet work, or the like, in an end grain manner which comprises, first treating the cypress with a solution of sodium silicate and then treating the cypress with an oil.

3. The method of preparing cypress to adapt it primarily for use in floors, wall covering, cabinet work, or the like, in an end grain manner which comprises, impregnating the cypress with a solution of sodium silicate and treating the cypress with an oil.

4. The method of preparing cypress to adapt it primarily for use in floors, wall covering, cabinet work, or the like, in an end grain manner which comprises, first treating the cypress with a solution of sodium silicate, allowing evaporation to take place, and then treating the cypress with an oil.

5. The method of preparing cypress to adapt it primarily for use in floors, wall covering, cabinet work, or the like, in an end

grain manner which comprises treating the cypress with a solution of sodium silicate and with a paraffin oil.

In testimony whereof I affix my signature.

SAMUEL D. BUTTERWORTH.
